CLAIM

The ornamental design for an organizer for assorted small articles, as shown and described.

DESCRIPTION

FIG. 1 is a top plan view of an organizer for assorted small articles showing my new design, the bottom view being a mirror image thereof;

FIG. 2 is a right side elevational view thereof;

FIG. 3 is a left side elevational view thereof;

FIG. 4 is a front elevational view thereof;

FIG. 5 is a rear elevational view thereof; and,

FIG. 6 is a top front left perspective view thereof.

The perforated pattern on the divider panels in FIGS. 5 and 6 is continuous throughout the area indicated.
